UNITED STATES PATENT OFFICE.

AUGUSTE ARTHUR CAILLE, OF DETROIT, MICHIGAN.

FOLDABLE RUDDER.

1,107,408.

Specification of Letters Patent. Patented Aug. 18, 1914.

Application filed December 6, 1913. Serial No. 805,011.

To all whom it may concern:

Be it known that I, AUGUSTE ARTHUR CAILLE, a citizen of the United States, and a resident of Detroit, in the county of Wayne and State of Michigan, have invented a new and Improved Foldable Rudder, of which the following is a specification.

This invention relates to a foldable rudder, and more particularly to one that is especially applicable to out board motors for small boats.

One object of this invention is to provide a rudder that may be readily turned to folded position, thereby reducing the space otherwise necessary for storage purposes.

Another object is to provide a foldable rudder, the bracket of which may constitute, when the rudder is in folded position, one member of a three point support for the motor and parts connected thereto.

The invention consists in a rudder that is connected to the rudder shaft of an outboard motor in such manner as to be readily turned from a position substantially parallel to the rudder shaft to a position at substantially right angles thereto.

This invention also consists in means whereby the rudder shaft may be adjustably mounted on the rear end of the boat.

It further consists in the novel details of construction shown and described and particularly pointed out in the claims.

Figure 1 is a perspective of the motor and rudder in position upon the rear end of a boat. Fig. 2 is a horizontal section showing the connection of the tiller to the rudder shaft. Fig. 3 is a fragmentary elevation of the rudder bracket and the adjacent end of the rudder.

Similar reference characters refer to like parts throughout the several views.

In the drawings, 1 indicates a well known form of bracket to hold a motor in position upon the rear end of a boat. Supported upon the bracket, by means of trunnions 2, is a motor 3 and a fuel chamber 4 that may be provided with lugs 5 upon its rear surface. Connected to the motor is a motor shaft casing 10, which is also supported upon the bracket 1, preferably by means of the split bracket 11, and projects downwardly from the crank case, its lower end being adjustable to and from the rear end of the boat by means of the slotted connection 12. This connection consists of a pair of slotted members, one on each side of the

motor shaft, that are mounted to swing in a vertical plane on the pin 15 passing through a perforation in the lower end of the bracket 1. The motor shaft casing and rudder carried thereby may be clamped in any position of angular adjustment by means of the bolt 30 and thumb-nut 31. Within the tubular casing 10 is a motor shaft 13 (Fig. 2) that turns the screw 14 at the lower end of the casing.

The parts thus far described, with the exception of the lugs 5 and the slotted connection between the bracket and the motor shaft, are well known.

Mounted to turn upon the sleeve 10, at a point preferably just below the crank case, is a tiller rod 16 having at its forward end a handle 17 and at its rear end a gear segment 18 that engages with a gear segment 19 secured to the upper end of a rudder shaft 21, the latter preferably being carried by the brackets 11 and 22 upon the casing 10. The rudder shaft has rigidly secured thereon, preferably at its lower end, a rudder bracket 23 that is provided with a split outer end 24 having a shoulder 25 formed upon its lower side, as shown in Fig. 3. The end 24 is perforated to receive a pin 26 and mounted to turn upon this pin and between the halves of the split end is a rudder blade 27 that is provided upon its lower edge with a lug 28 which is adapted to contact with the shoulder 25 and thereby limit the angular adjustment of the blade. The blade is preferably tightly gripped by the halves of the end 24, which prevents accidental displacement, but at the same time allows the blade to be turned from the dotted line position to that shown in full lines in Fig. 1. In use the blade is in the position shown in dotted lines.

If it is desired to store away the motor, it is detached from the boat, and the rudder is then swung into the full line position, after which the motor may be supported in the bottom of the boat or elsewhere by means of the lugs 5 and the outer end of the rudder bracket 23.

Any desired changes may be made in the details of the device without departing from the spirit of my invention as expressed in the claims.

Having now described my construction, what I regard as my invention and desire to secure by Letters Patent is:—

1. In combination, a support, a motor shaft casing carried thereby, brackets se-

cured on the casing and having alined bearings, a rudder shaft mounted to turn in the bearings, means to turn the rudder shaft, a rudder bracket secured to the rudder shaft 5 to turn therewith, the bracket comprising a split outer end, and a shoulder, a rudder pivotally mounted in the split outer end and also provided with a shoulder, the two shoulders being adapted to contact with each 10 other to limit the movement of the blade in one direction.

2. In combination, a support, a motor and a fuel chamber carried thereby, lugs projecting from the fuel chamber, a bracket secured to the casing and having a bearing formed therein, a rudder shaft mounted to turn in the bearing, a rudder bracket secured to the rudder shaft, a foldable rudder connected to the bracket, said rudder bracket 15 and said lugs being adapted to constitute a support for the motor when the rudder is in folded position.

3. In combination, a support, a motor shaft casing carried thereby, a bracket 20 mounted on the support and having a bearing therein, a rudder shaft mounted in the 25

bearing, means to turn the rudder shaft, a rudder bracket secured to the rudder shaft to turn therewith and having a shoulder, a rudder blade pivotally mounted on said rudder bracket, and also provided with a shoulder, the two shoulders being adapted to contact with each other to limit the movement of the rudder in one direction. 30

4. In combination, a support, a motor shaft casing carried thereby, a bracket mounted on the support and having a bearing therein, a rudder shaft mounted in the bearing, means to turn the rudder shaft, a rudder bracket secured to the rudder shaft 40 to turn therewith, a rudder pivotally mounted on said rudder bracket, and means on the rudder co-acting with means on the rudder bracket for limiting the movement of the rudder in one direction. 45

In testimony whereof I have signed this specification in the presence of two subscribing witnesses.

A. ARTHUR CAILLE.
